UNITED STATES PATENT OFFICE.

PETER J. VOLLMAN, OF CHICAGO, ILLINOIS.

THERMOSTATIC VALVE.

1,363,447.

Specification of Letters Patent. Patented Dec. 28, 1920.

Application filed December 4, 1918. Serial No. 265,238.

To all whom it may concern:

Be it known that I, PETER J. VOLLMAN, a citizen of the United States, and a resident of Chicago, in the county of Cook and 5 State of Illinois, have invented certain new and useful Improvements in Thermostatic Valves, of which the following is a full, clear, and exact description.

The invention relates to automatic thermostatic valves or traps for use in connection with heating systems.

The object of the invention is to provide an improved thermostatic valve of this character which is simple in construction and efficient in operation and which can be easily assembled and disassembled. Other objects of the invention will appear more fully from the description.

The invention consists in the several novel 20 features hereinafter set forth and more particularly defined by claims at the conclusion hereof.

In the drawings: Figure 1 is a central vertical section of a valve embodying the invention. Fig. 2 is a plan, the thermostat and cap being removed. Fig. 3 is a detail of the device for holding the thermostat in the cover.

The valve comprises a casing 4 provided 30 with a horizontal nipple 5 which is adapted for connection to a suitable coupling 6 to connect the valve to the outlet of a radiator. An inlet-chamber 7 is formed below and adjacent the inlet 5 by an oblique cross-wall 8 and a portion of the outer wall of the casing. This chamber is formed to serve as a mud trap. This wall 8 is provided with a seat for a valve 10 which is slidably held in a bridge 11 integrally formed with the casing 4. The axis of the valve is oblique and the valve is located in an outlet chamber 12 formed on the other side of the oblique wall 8. The casing is provided with a vertical nipple 13 to which an outlet pipe is adapted 40 to be connected so that fluid from the chamber 12 will pass into the return line of the heating system or other system. Valve 10 is held normally open by a flat spring 14 which has slotted ends held by screws 15 in 45 the lugs 16 formed inside of the casing. By adjusting these screws, the operation of the valve 10 may be regulated as desired.

The central portion of this spring 14 bears 50 against a shoulder 17 on the valve 10 to yieldingly hold the valve open. The casing is provided with a screw-threaded ob-

lique opening which is closed by a cap 19 and the latter is screw-threaded to the casing and also oblique or inclined. This cap contains the thermostat 20 which is of the 60 capsule type and is adapted to engage the upper end of the valve 10 to force the valve to its seat when the thermostat is expanded by the heat. A split ring 21, held in a groove 22 in the cap, serves to removably 65 hold the thermostat in the cap. A screw 23 serves as an adjustable abutment for the thermostat. A screw-plug 25, accessible from the outside of the valve, is adapted, when open, to permit the mud in the pocket 70 to discharge into the outlet.

A characteristic of the valve illustrated and described is that the axis of the valve, cross-wall 8 and cap 19 are inclined or disposed obliquely with respect to the horizontal 75 inlet and the vertical outlet of the casing. As a result of this arrangement, a number of important advantages are attained. It makes it possible to dispose the valve-seat or passage in the cross-wall 8 below the lowest portion of the inlet so as 80 to insure drainage of the inlet at all times when the valve is open. It also makes it possible to avoid objectionable or undue projections on the valve and also makes it possible 85 to bring the axis of the vertical outlet close to the radiator or inlet. The oblique wall, in which the valve-seat is formed, also serves as a deflector for the fluid to direct it downwardly toward the valve-seat below 90 the inlet. By providing a spring for holding the valve normally open, there is no danger of the valve becoming stuck to its seat in low pressure heating systems. The split ring provides means for retaining the 95 thermostat in the cap so that it will be removable with the cap and the conjoint removal of the cap and thermostat is advantageous in assembling and disassembling the valve. By adjusting the screws which hold 100 the spring for opening the valve, the latter may be made responsive to different pressures.

The invention is not to be understood as restricted to the details set forth, since these 105 may be modified within the scope of the appended claims, without departing from the spirit and scope of the invention.

Having thus described the invention, what I claim as new and desire to secure by Letters Patent, is:

1. In a thermostatic valve, the combina-

tion of a casing having inlet and outlet connections, a valve for controlling communication between the inlet and the outlet, a spring for opening the valve, a thermostat of the capsule type for closing and supported independently of the valve, said casing being provided with an opening, a cap for closing said opening having a chamber therein in which the thermostat is disposed, and means engaging the margin of the capsule for holding the thermostat in said chamber.

2. In a thermostatic valve, the combina-

tion of a casing having inlet and outlet connections, a valve for controlling communication between the inlet and the outlet, a spring for opening the valve, a thermostat of the capsule type for closing and supported independently of the valve, said casing being provided with an opening, a cap for closing 15 said opening having a chamber therein in which the thermostat is disposed, and a ring 20 engaging the margin of the capsule for holding the thermostat in said chamber.

PETER J. VOLLMAN.
